2,074,120

PROCESS AND APPARATUS FOR PRESSURE DISTILLATION

David G. Brandt, Westfield, N. J., assignor to
Doherty Research Company, New York, N. Y.,
a corporation of Delaware

Application July 23, 1926. Serial No. 124,320

4 Claims. (Cl. 196—48)

The present invention relates to the cracking of heavier hydrocarbons to obtain lighter hydrocarbons therefrom and more particularly to obtain from gas oil or like material a finished motor spirit or gasoline. The invention of the present application is an improvement upon my prior pending applications Ser. No. 710,996 and Ser. No. 654,532, filed May 5, 1924 and July 30, 1923, respectively the last of which has matured into 10 Patent No. 1,872,879, Aug. 23, 1932.

1 In my said prior applications, I have disclosed
2 a process and apparatus for the pressure distilla-
3 tion of relatively heavy hydrocarbons to obtain
4 pressure benzine therefrom, said prior applica-
15 tions disclosing passing charging stock of the
16 character of gas oil, or the like into a cracking
17 chamber. A mixture of hydrocarbons is then
18 withdrawn from the cracking chamber and forced
19 through a pipe still or heating coil where the mix-
20 ture is heated to cracking temperature. From the
21 pipe still the heated oil is discharged into a sepa-
22 rating chamber wherein the liquids and vapors
23 separate and both the liquids and vapors are
24 taken from said separator into a vertical crack-
25 ing chamber in which the vapors are passed in
26 countercurrent relation to the liquids while still
27 at cracking temperature and under pressure to
28 complete the cracking reaction. Vapors from
29 said cracking chamber are passed through a
30 dephlegmator, the reflux from which is run back
31 into the cracking chamber and uncondensed gases
32 and vapors from which are passed through a
33 pressure controlling and reducing valve and
34 thence to a condenser. My prior application Ser.
35 No. 532,954 filed Jan. 31, 1922, which has matured
36 into Patent No. 1,784,087, Dec. 9, 1930, discloses
37 also drawing off heavy liquid from the bottom or
38 lower portions of said cracking chamber and re-
39 lieving pressure thereon to permit the heat con-
40 tained in the liquid so drawn off to drive over a
pressure distillate which is condensed, the resid-
uum liquid resulting after the passing off of said
distillate being used for fuel or other purposes.

Certain objects of the present invention are improving the results obtained from my said prior processes and apparatus by controlling the circulation of the liquids in said vertical cracking chamber to prevent the mixing of the feed with the liquid from the separator within the cracking chamber proper; to obtain a finished gasoline from a cracking plant; and to conserve and return to the process part of the heat formerly lost in the residuum drawoff.

The novel features of the present invention are pointed out with particularity in the appended claims. The invention itself, however, together with further objects and advantages, will best be understood from the following description taken in connection with the accompanying drawing in which:

REISSUED

The figure is an elevational view, partly diagrammatic in character, of an apparatus adapted to operate in accordance with the method or process of the present invention and including the novel features hereinafter described and claimed. 5

In the apparatus illustrated in the drawing, raw charging stock, preferably gas oil, is brought in through pipe 2 to the feed pump 4 and thence forced through pipes 6 and 8 to the upper portion of a tower 10 combining the functions of a heat exchanger, a bubble cap tower and a dephlegmator. The pipe 8 enters a chamber 12 at the top of the tower 10 and the oil thereupon passes through a coil or heat exchanger 14 within chamber 12 and thence through coils 14a, 14b, 14c, and 14d in the chambers 12a, 12b, 12c, and 12d arranged below the chamber 12 in the tower 10 and in the order mentioned in going from the top to the bottom of the tower. The chambers 12, 12a, 12b, 12c, and 12d inclusive, and if desired others of like character not illustrated, comprise the bubble-cap or tray section of the tower 10 through which reflux passes downwardly from one chamber to the other and vapors pass upwardly as indicated by arrows in counterflow to the reflux in a well-known manner, this type of apparatus being so well-known that the details of the bubble caps are omitted from the drawing. It will be seen that the bubble cap section of the tower 10 according to the present invention differs from the standard bubble cap apparatus primarily in that the chambers of the individual trays of the bubble cap section of tower 10 include coils 14, 14a, 14b, 14c, 14d in contact with the vapors in the chambers and through which the ingoing charging stock passes in series, these coils thereby acting as heat exchangers, heating the ingoing stock at the same time that they condense a portion of the rising and outgoing vapors to increase the reflux condensate normally formed in such apparatus. Below the chamber 12d, tower 10 comprises two or more dephlegmating chambers 16, to which vapors pass in series on their way to the bubble cap section of the tower 10. Owing to the character of chamber 16 the bottom 15 of chamber 12d is not of the bubble-cap type but is perforated substantially uniformly to act as distributor for reflux liquid passing down thru it. Chambers 16 are partly filled with fragments 18 of glass, coke or other inert material to increase the dephlegmating effect. The lumps or fragments 18 rest on horizontal perforated partitions supported within tower 10 at the lower ends of the chambers 16. Lower chamber 16 contains also coil 20 through which the charging stock passes after leaving the coil 14b previously mentioned, coil 20 having the same function as the coils 14, 14a, etc. in the upper portion of tower 10. Directly below the lower chamber 16

ber 16 is a chamber 16a in which is mounted a coil 20a similar to and connected in series with the coil 20. The stock being charged into the apparatus through coils 14, etc. 20 and 20a is discharged into the chamber 16a where it is mixed with reflux flowing down into chamber 16a from upper chambers in the tower 10 as well as with that formed in chamber 16a. The bottom of the chamber 16a is formed of two perforated plates spaced apart, the space being filled with fragmentary material 18 of the type referred to above. This arrangement causes intimate contact over an extended area, of the vapors entering and the liquids leaving the tower 10.

15 The dephlegmating tower 10 preferably is set on top of a heat insulated cracking chamber 24, there being a frustro-conical plate 26 at the bottom of tower 10 and separating the tower from the cracking chamber 24. The plate or partition 26 has a central aperture 28 through which reflux condensate from the tower discharges into the cracking chamber. Charging stock after passing through the coil 20a and mixing with reflux in chamber 16a is discharged downward 25 centrally through the opening 28 into the cracking chamber along with the reflux condensate. The cracking chamber 24 contains a considerable body of material which has been either cracked previously or is undergoing cracking and, according to the present invention, it is desired to prevent the reflux from tower 10 and the charging stock from mixing immediately with such material in chamber 24 until the material in the chamber has substantially completed the cracking 35 action obtainable without reheating. According to the present invention therefore, a central conduit 30 of large dimension is set vertically beneath the aperture 28 to receive the reflux and charging stock coming down through the aperture. Preferably conduit 30 carries at its upper end funnel-shaped mouth 32 for receiving the reflux and charging stock and guiding it into the conduit 30. Below the chamber 24 and spaced therefrom by a diaphragm 34 is a mixing 40 chamber 36 and conduit 30 extends through the diaphragm 34 so as to conduct the mixed reflux and charging stock through chamber 24 and into the mixing chamber 36 before the charging stock and reflux can mix with the material from chamber 24. Material which has undergone cracking in chamber 24 passes from the lower end of said chamber into the mixing chamber 36 through pipes 38, 38. The mixture of reflux, charging stock and previously cracked material, 45 in the proportions of about 60% previously cracked stock to 20% fresh stock and 20% reflux, is taken out of chamber 36 through pipe 40, returned to the system and forced by pump 42 through pipe 44 to a pipe still or heating coil 46 contained in the furnace 48. Any gas oil obtained as described below by separating it from the liquid taken out of chamber 24 is included in the 50 20% fresh stock just mentioned. Ordinarily, the liquid passing through coils 14a, 14b, etc. in tower 10 is only 10% of the liquid entering pipe still 40 from pump 42 and is seldom more than 20%. In most aspects however, the present invention is independent of the ratio between the liquid flowing through coils 14a, 14b, etc. and that pumped into pipe-still 46. In the coil 46, the oil is heated to between 750° and 900° F. under considerable pressure and discharged through pipe 50 to the upper portion of the separator 52. Vapors from separator 52 pass out 55 of the top of the separator through pipe 54

which passes through the side of the cracking chamber 24 and discharges into a distributor 56 near the bottom of the cracking chamber. Liquids entering the separator 52 pass to the lower portion of the separator through the interior of conduit 58 and the majority of these liquids leave the separator through a pipe 60 which passes through the side of the chamber 24 somewhat above the mid-level of the liquids therein and discharges directly into the chamber. The liquid discharged from pipe 60 thereupon works its way downwardly through the chamber 24 while undergoing further cracking and in a general way countercurrent to the vapors and gases discharged from the distributor 56. The majority of the liquids flowing downwardly in the chamber 24 as just mentioned and remaining unvaporized passes through the pipes 38, 38 into the mixing chamber 36.

10 It has been found that the cracking reaction 20 is one requiring an appreciable amount of time in which to complete itself. If the cracking reaction initiated by a given heating of the oil has not been permitted to complete itself before the oil is returned to the cracking coil, the oil which 25 has not completed its cracking from a previous heating is almost sure to crack in the pipe still when returned thereto. The excessive cracking of the oil in the pipe still is undesirable, not only because of the carbon which may thereby be deposited in the pipe still, but because of poor utilization of the heat imparted to the oil if the cracking has not been completed in the chamber 24. The capacity of the separator chamber 52 is preferably made such that the oil 30 is held in chamber 52 until it is "conditioned", or about to crack, before being transferred to chamber 24. The oil as introduced into chamber 24 being about to crack, the contact of the hot oil with the hot gases coming from the top of separator 52 and distributed through the oil in chamber 24 by the distributor 56 produces a rapid cracking action in the chamber 24. Moreover, the distributor 56 being adjacent the outlet 35 from chamber 24 any oil leaving this chamber 40 must come into contact with the hottest gases, thus insuring that any molecule of the oil which has absorbed enough heat in coil 46 to be chemically unstable will crack before leaving chamber 24. The heat delivered to the oil in the pipe 45 still is therefore effectively utilized in chambers 50 52 and 24 and very high firing rates can be applied to the pipe still without depositing an objectionable amount of carbon in the coil 46. The capacity of the apparatus is therefore very high 55 for a given area of heating surface in the coil 46. In addition to the advantages just discussed, the gases and vapors delivered to the lower part of chamber 24 by the distributor 56 and rising through the liquid in the chamber strip out of the liquid undergoing cracking in the chamber 60 substantially all of the gasoline-like material in this chamber. The formation of gasoline-like material in the oil heated in pipe still 46 is therefore promoted to a maximum degree owing to the 65 substantial absence of any gasoline-like material in the feed to the still. In this connection, experience has shown that a partial pressure of gasoline in material being heated to cracking temperature correspondingly reduces the amount 70 of gasoline formed by a given heating.

It is necessary that a certain amount of liquid be withdrawn from the cracking still, not only to prevent the liquid level in the apparatus from becoming too high but also to maintain the proper 75

quality of the liquid in the cracking circuit for optimum conditions of operation. I have found that processes and apparatus employing a cracking circuit according to my said prior applications are operated with a minimum of difficulty while at the same time giving large yields of gasoline when substantially no free carbon can be detected in the liquid in the chamber 24. This is not to be taken to mean that no carbon forms in chamber 24, as the metal surfaces within this chamber which are exposed to the hot oil accumulate a layer of crystalline carbon, the metal seemingly catalyzing the separation of carbon from the liquid undergoing cracking. Nevertheless the liquid itself within the chamber 24, under the conditions desired according to the present invention, contains practically no free carbon.

In order to maintain the desired condition of the liquid as to free carbon which has just been mentioned, the shell of chamber 24 moreover is tapped slightly above diaphragm 34 and an outlet pipe 62 connected into the shell at this level through which residuum may be drawn off at the rate desired from the chamber 24, the flow of liquid through pipe 62 being regulated by valve 64.

It is observed, moreover, in order to maintain the optimum operating conditions in the cracking circuit that some of the heavy residuum should be withdrawn from the bottom of the separator 52. For this purpose, the valved pipe 63 is led out of the bottom of separator 52, pipe 63 connected with the pipe 62 through which residuum is taken from chamber 24.

While, according to the present invention, it is desired to prevent the formation of free carbon mixed with the liquid in the chamber 24, the presence of a small amount of free carbon in the liquid taken out of the bottom of separator 52 through pipe 63 is not harmful. As a general rule, the oil passing through pipe 62 to the concentrator is made up of about 60% of material taken from the bottom of the cracking chamber 24 and about 40% of material from the separator 52 although all of it may be withdrawn from 24 or 52.

Pipe 62 delivers liquid into chamber 66 in the bottom of a concentrator 68. The pressure in concentrator 68 is substantially reduced as compared to that in the chamber 24 and gasoline and gas oil contained in the liquid entering chamber 66 are thereby permitted to evaporate under the reduced pressure and due to the heat contained in the incoming liquid itself.

For instance, if chamber 24 is at 250 lbs. gage pressure, concentrator 68 is operated at about 50 lbs. gage to give a certain gravity to the residuum withdrawn from chamber 66. The proper pressure to hold in chamber 66, therefore, varies with the pressure and temperature in chamber 24 as well as with the grade of residuum or fuel oil desired. Moreover, when a fuel oil is desired of a gravity heavier than that readily obtainable merely by reduction of pressure under the conditions prevailing at a given time, steam or gas may be introduced into the lower part of chamber 66 to assist vaporizing liquid in this chamber. Vapors formed in chamber 66 pass out of the chamber through the opening 70 in the diaphragm 72 which forms the top of the chamber 66. The vapors from opening 70 pass into a bubble cap tower comprising chambers 14, 14a, 14b, and 14c in the upper part of the concentrator 68. The bubble cap portion of the concentrator comprises bubble cap sections or trays which may be

of standard or other preferred design and the details of which are not illustrated. It will be understood, however, that the vapors pass up through chambers 14, 14a, 14b, and 14c, the heavy vapors being condensed and flowing as a reflux back into chamber 14. To assist in the formation of reflux and to prevent any vapors heavier than gasoline from passing out of concentrator 68, a cooling coil 76 is placed in the top of the chamber 14c. Gasoline vapors passing the coil 76 are taken out of the top of the concentrator 68 through pipe 78 and passed thence through condenser 80 to suitable storage tanks. Reflux condensate, however, formed in bubble cap sections 14, 14a, 14b and 14c is not permitted to flow back into chamber 66 at the bottom of the concentrator 68 but, owing to the form given the diaphragm 72, and the outlet 70 therethrough, is trapped in the lower portion of the chamber 14 from which the condensate, consisting principally of gas oil may be drawn out through pipe 82 and forced by pump 84 back through pipe 86 into the mixing chamber 36 mentioned above. By the arrangement and method just described, much of the heat of the residuum drawn from the bottoms of chamber 24 and 52 may be returned to the cracking circuit with the gas oil or the like from concentrator 68. The gas oil from chamber 14 may, of course, be stored and mixed with or used in place of gas oil from other sources. On the other hand the portion of the liquid from the lower part of chamber 24 which enters the chamber 66 and which does not vaporize at the pressure and temperature in chamber 66 is taken out of the lower part of this chamber through pipe 88 and passes through a cooler 90 from which it is taken to suitable storage. This liquid is a fuel oil.

In the operation of valve 64 and the valve in pipe 63 to admit liquid into chamber 66 from the cracking chamber 24, and the separating chamber 52, it is preferred that the valves be opened to their fullest extent whenever liquid is to be passed through them and closed tight again as soon as the desired amount of liquid has been withdrawn through them. I have found that this way sticking of valve 64 and of the valve in pipe 63 is avoided. When these valves are only cracked open to permit the desired amount of liquid to flow through them continuously, the valves soon become inoperative due to gum and carbon adhering to them and to their seats.

Gases and vapors liberated from the surface of the oil in chamber 24 pass through the aperture 28 and into the dephlegmator 10. Here the vapors are dephlegmated, the dephlegmating action due to the outer surface of tower 10 being assisted both by the cooling of the vapors by the coils 14, 14a, 14b, 14c, 14d, 20 and 20a previously mentioned and by pumping a volatile liquid such as gasoline into the chamber 12 of tower 10. The design and arrangement of the coils 14, 14a, 14b, 14d, 20, and 20a is such that the dephlegmating action is least in the section of tower 10 in which the vapor temperature is highest and is increased by steps to the section or chamber of the tower 10 in which the vapor temperature is lowest. It will be seen, moreover, that the increase in dephlegmating effect in the direction of decreasing temperatures in tower 10, in other words, in the direction of flow of the vapors being dephlegmated, is as specifically disclosed, a product of three factors; namely, the increasing area of the coils 20a, 20, etc. in the direction of flow of the vapors, the decreasing temperature of the raw liquid in the coils 20a, 20, etc. and the volatile

liquid injected into the uppermost chamber 12 of tower 10. By thus graduating the dephlegmating effect and increasing it in the direction of flow of the gases, the temperature at the lower or hotter end of tower 10 may be at a maximum temperature, with minimum of reflux at this point, thus producing optimum conditions for the escape of gasoline from the cracking chamber 24 both as to temperature and as to reduction of mechanical entanglement of gasoline vapors in the reflux. The temperature at the upper end of tower 10 is, however, maintained such that no vapors heavier than those of commercial gasoline pass out of tower 10, and I am thus enabled to produce commercial or "end-point" gasoline direct from the vapors of a cracking chamber without rerunning the distillate to eliminate heavy ends as is now the practice.

Of course it is impossible to maintain an absolutely constant rate of cracking in chamber 24. The dephlegmating effect of tower 10 must therefore be varied to produce the desired end point gasoline. The variation of the cooling effect in tower 10 required by variations in the rate of cracking in the chamber 24 is obtained by varying the amount of gasoline pumped back into the chamber 12.

It has been found possible to attain the desired results as to the temperature in the tower 10 and particularly in the upper end thereof by automatically controlling the speed of the pump 106 which returns gasoline to the tower in accordance with the temperature of the vapors passing from the tower to the condenser. A satisfactory method and arrangement for operating pump 106 in accordance with the temperature of the vapors in tower 10 is disclosed in my prior application No. 654,532, filed July 30, 1923. However, I do not limit myself to automatic control of pump 106 as this pump may be controlled by hand within the present invention. These vapors pass through an offtake pipe 92, containing a pressure-maintaining valve 100, valve 100 preferably being in duplicate so that one may be used if the other is out of order. It has been found moreover according to the present invention, that maintaining the temperature in the top of the tower 10 at the point producing by condensation a given end point gasoline from the vapors which have passed therethrough, also automatically maintains the pressure in the dephlegmator 10 substantially constant and avoids the necessity of adjusting the valve 100 during the normal operation of the apparatus. Maintaining a constant pressure in tower 10 also of course automatically maintains substantially constant pressures throughout the other parts of the apparatus.

Vapors not condensed in dephlegmator 10 pass out of the top thereof through pipe 92 to condensers 94, 96, and 98 through which the vapors pass in series. Intermediate tower 10 and condenser 94, the pressure is reduced by controlling valve 100 previously mentioned. Condenser 94 is the first condenser through which vapors from pipe 92 pass. Gasoline condensed in condenser 94 passes through pipe 102 to a container 104. Vapors uncondensed in the condenser 94 then pass through the condenser 96 and finally through condenser 98. Condensate from condenser 96 passes through pipe 109 to container 110 and vapors, condensate and gases from condenser 98 pass through pipe 112 to container 110. Uncondensed gases and vapors pass off from the receiving tank or container 110 through pipe 114. Gas 75 or vapors from container 104 also may pass

through pipe 116 into the top of container 110 and thence off through pipe 114. Pipe 114 may lead to burners or to other means for utilizing the gas and uncondensed vapors. Preferably the gas in pipe 114 is scrubbed for gasoline before being utilized. Gasoline from tank 110 is run to gasoline storage through pipe 118, the flow through pipe 118 being conveniently regulated by an automatic valve 120 operated by a float in chamber 122.

As mentioned above, the satisfactory control of the dephlegmating effect in tower 10 and more particularly the control of the dephlegmating effect in the top chamber of the dephlegmator has been found to be best achieved by introducing into chamber 12 a varying amount of gasoline of the end point it is desired to make in the apparatus. For this purpose a pump 106 is provided whose intake is connected by pipe 123 with the tank 104. Pump 106 forces gasoline received by it from pipe 123 into chamber 12 through pipe 108 to maintain a constant end point on the gasoline formed from the vapors leaving chamber 12. The necessary variations in the amount of gasoline pumped to dephlegmator 10 to compensate for changes in the vapor flow therethrough are readily produced by thermostatic control of the speed of pump 106, a thermostat (not shown) for this purpose being connected into the vapor line 92.

Liquid gasoline from the condenser has a cooling effect when introduced into tower 10 due both to its temperature and to its vaporization at the temperatures in the tower. The gasoline from tank 104 moreover, is preferably introduced into chamber 12 in sufficient quantity so that a considerable portion of it does not vaporize in chamber 12 when pumped thereinto, but runs down into chambers below chamber 12 before vaporizing. Advantage is therefore taken in the design of dephlegmator or tower 10 of the cooling effect of the heavy gasoline from condenser 94 when pumped back into the chamber 12 by correspondingly reducing the size of the cooling coils in the chambers below the top tray.

All the gasoline from condenser 94, however, is not required to be put back into chamber 12 and gasoline from tank 104 not used by pump 106 flows through valve 126 in pipe 124 to pipe 118 and thence to storage. Similarly, gasoline from condensers 96 and 98 collects in tank 110 and flows from this tank to storage through pipe 118. A valve 120 in pipe 118 is controlled by a float in float tank 122 connected to tank 110, so as to maintain a substantially constant level of gasoline in tank 110.

In addition to the pipe connections previously mentioned as used in the operation of the apparatus and process according to the present invention, there are illustrated in the drawing certain pipe connections used only on particular occasions. For instance, the vapor line 54 leading from the top of the separator chamber 52 to the cracking chamber 24 has a branch pipe 128 connected thereto and leading into the chamber 24 above the normal liquid level in chamber 24 and whereby the pressure above the liquid in chambers 24 and 52 may be equalized when it is desired to draw out the liquid in the chambers when for any reason the apparatus is shut down. A valve 129 is provided in the pipe 128 normally preventing passage of vapors through the pipe. Moreover, the feed line 6 for the raw oil has a pipe connection 130 passing

through the side of the chamber 24 above the conduit 30 and arranged to deliver more or less of the feed into the upper end of the conduit 30 whenever for any reason it is not desired that

5 the entire feed pass through the cooling coils 14, 14a and 14b, etc. and tower 10. Also, special draw-offs are provided from chambers 36 and 52 for taking out liquid from the lower ends of these chambers whenever it is desired to drain

10 the liquid from these chambers. For this purpose valved pipe 132 leads from the bottom of chamber 36 connecting with the pipe 62 and valves by-pass 134 connects the pipe 82 with pipe 78 for permitting reflux collecting in chamber

15 74 to pass into a recycle gas oil tank. Similarly a valved pipe 136 is connected into the lower end of chamber 52 and arranged to deliver to pipe 62. Another way of discharging oil from chambers 36 and 52 is provided by a

20 pipe 138 connected at one end to a pipe 88 and coil 90, connection being provided from the coil 90 to a relief tank. When desired, liquid may be discharged from chambers 36 and 52 into pipe 138 and thence into the relief tank through

25 valved pipe connections 140 and 142 respectively. Moreover, provision is made whereby, when desired, some or all of the liquid going through the pump 42 may be circulated through the chambers 52, 24, and 36 without passing through the

30 pipe coil 46. The arrangement for this purpose comprises a connection between the pipes 138 and 44 including a valve 144. By opening the valve 144 and the valves in pipes 140 and 142, when flow from pipe 138 to pipe 88 is cut off the

35 pump 42 may be kept in operation while little or no cracking is being carried out. It is preferred, moreover, that the valves in pipes 132 and 136, as well as other valves which may be used to draw off partially cracked material from

40 chambers 24 and 52 during the normal operation of the apparatus shall be operated like valve 64 so as to be open to the fullest extent when it is desired to draw off liquid and to close them tight at other times.

45 While an apparatus according to the present invention and adapted to operate in accordance with the process of the present invention is illustrated in the accompanying drawing and described herein in detail it should be understood that such detailed disclosure is illustrative only and is not intended as limiting the scope of the appended claims.

50 The separator and cracking chamber have been shown as being insulated. The usual practice for cracking stills is to insulate all equipment including pipe lines which handle hot oil. This insulation is not illustrated in the drawing for the sake of clearness.

55 Having thus described my invention, I claim:

60 1. In an apparatus of the class described, a cracking chamber, a mixing chamber connected to the lower end of said cracking chamber, a dephlegmator set over said cracking chamber and receiving vapors therefrom, a central conduit in said cracking chamber, the upper end of which stands above the normal level of liquid in the chamber and the lower end of which connects directly with said mixing chamber, and means whereby reflux from said dephlegmator and fresh stock charging liquid pass directly into said conduit.

65 2. The method of treating a relatively heavy hydrocarbon oil to produce a relatively light hydrocarbon therefrom comprising heating said relatively heavy hydrocarbon to cracking temperature while under pressure, removing said heated hydrocarbon from the heating conditions and permitting it to crack under insulating conditions from heat previously stored therein, distilling a portion of said cracked hydrocarbon to produce a gas oil and a fuel oil, dephlegmating 10 vapors produced by said cracking reaction, pre-heating oil by said vapors, withdrawing residual hydrocarbon from that undergoing cracking and mixing it with additional hydrocarbon for heating to continue the process, the mixtures so 15 formed comprising 10% of stock preheated by the vapors undergoing dephlegmation, 20% of liquid reflux obtained by dephlegmating said vapors, and 10% of said gas oil derived by distillation from previously cracked material. 20

25 3. The process of cracking high boiling point hydrocarbons to produce relatively low boiling point constituents of the nature of gasoline, which comprises maintaining a body of high boiling point hydrocarbons in a cracking zone under cracking conditions of temperature and pressure, subjecting the vapors evolved from the hydrocarbons in said zone to reflux condensing conditions to separate high boiling point constituents from relatively lower boiling point constituents, passing the reflux condensate produced into a charge mixing zone, withdrawing heavy liquid hydrocarbon material from said cracking zone into a single vaporizing zone and 30 vaporizing substantial portions thereof under a substantially reduced pressure by heat contained therein, subjecting the resulting vapors to reflux condensing conditions and passing the resulting reflux condensate free of the resulting unvaporized residue in said vaporizing zone into 35 said mixing zone, withdrawing oil mixture from said mixing zone and forcing it under a superatmospheric pressure through a heating zone in which the oil is heated to a cracking temperature, and passing the resulting highly heated 40 products into the body of oil in said cracking zone. 45

4. In the process of cracking hydrocarbon oils including heating a relatively heavy hydrocarbon oil to cracking temperature under pressure, in which relatively high-boiling oil constituents previously subjected to cracking conditions are admixed with fresh stock and the resulting mixture circulated in a closed cycle including a heating zone maintained under cracking conditions of temperature and superatmospheric pressure, the improvement which comprises withdrawing a portion of said mixture being circulated into a single vaporizing zone and substantially reducing the pressure thereon to permit the heat contained therein to vaporize all of the constituents desired to be separated from said withdrawn mixture, dephlegmating the vapors formed to permit separation of gasoline vapors from the remainder of the vaporized material by reflux condensation, and passing the refluxed condensate from such dephlegmation step free of the resulting unvaporized residue in said vaporizing zone to said circulating mixture. 50
